LOAD TRANSFER DEVICE

Ray Cyrus Yeoman, Lufkin, Tex., assignor to Texas Foundries, Inc., Lufkin, Tex., a corporation of Texas

Application February 18, 1954, Serial No. 411,180

4 Claims. (Cl. 94—8)

This invention relates to a load transfer device of the type described in my earlier issued Patents No. 2,261,602 and No. 2,355,771. It relates more particularly to improvements in load transfer devices of the type described for interconnecting adjacent slabs of concrete in a manner to equalize the forces existing during manufacture and use and to reinforce the edge portions of the concrete slabs.

This and other objects and advantages of this invention will hereinafter appear and for purposes of illustration, but not of limitation, embodiments of the invention are shown in the accompanying drawings in which—

Figure 1 is an elevational view of a load transfer device embodying features of this invention in position of use in road construction;

Figure 2 is a perspective view showing the separated elements of the load transfer device of Figure 1, and

Figure 3 is a top plan view of the assembly shown in position of use in Figure 1.

The improvements embodying features of this invention will be described in a load transfer device 10 used in bridging the space 11 that is usually provided to enable expansion and contraction between two concrete slabs 12 and 13 laid in end to end relation upon a subgrade 14 to form a road bed in the form of a substantially endless strip of concrete. The space between the slabs is usually filled with a filler 15 such as a wood board capable of expansion and contraction in response to movement of the slabs for maintaining a sealing relation therebetween and asphalt 16 or other water-repellent material capable of plastic flow is provided at the upper end portion to minimize infiltration of free water, dirt or other foreign substance which might otherwise interfere with the normal operation of the assembly.

Anchored to the board filler 15 in laterally spaced apart relation, preferably in the area intermediate the top and bottom edges, are a plurality of load transfer devices 10 each of which is formed of a pair of substantially identical metal parts A and B formed of corrosion resisting metal, such as by casting of malleable iron or the like. The elements A and B are substantially identical in shape, each including a body portion 17 of rectangular cross section having a greater length than width and with a rectangular recess 18 of smaller dimension formed in one face thereof extending to the inner edge with walls 19, 20 and 21 all around the outer three edges.

Integral with the body portion 18 and extending curvilinearly rearwardly from the upper edge thereof is a tension arm 22 having a number of ribs 23 spaced through the length thereof for reinforcement and to enhance the anchorage relation of the arm and the body portion to which it is attached in the concrete. The tension arm is also formed preferably with a downwardly turned end portion 24 to provide a gripping relation which functions somewhat as the root of a tree to anchor the tension arm into the concrete slab into which it extends substantially to form an integral part thereof.

2

Integral also with the body portion 17 is a compression arm 25 which extends rearwardly from the lower portion of the end wall and which is provided with a button 26 on the end of the arm to achieve a desired bonding and anchoring relation between the compression arm and the body of concrete into which it extends. Instead of forming the compression arm as a member which extends rearwardly from the end wall as described, the compression member may be formed as a curvilinear arm, similar to that of the tension arm previously described but in which the end portion extends upwardly to provide the desired anchoring relation and in which the arm extends rearwardly from the lower wall of the body portion.

Integral with the body portion 17 and extending forwardly from the forward edge thereof defined by the recessed portion and flush with the inner face thereof is a cantilever bridging plate or arm 29 of corresponding shape but of slightly lesser width and thickness than the recess 18 in the body portion so that the cantilever bridging arm of one of the elements will be received in the recess of the other with slight clearance between the side walls. Except for the clearance, the purpose of which will hereinafter be described, the elements respond generally to the constructions which have heretofore been used in load transfer devices as defined in the patents previously mentioned.

The parts are interconnected in an assembled relation with the two substantially identical castings being joined in face to face relation with the cantilever bridging arm 29 of one being received in the recess 18 of the other with a spaced relation between the inner ends of the body portions providing a groove 30 dimensioned to correspond to the thickness of the filler strip 15 to enable a mounting relation to be effected on the strip through notches provided therein. The assembled relation is maintained by a bolt 31 and nut 32 or other similar joining means operating through an opening 33 in an intermediate portion of the cantilever bridging arm and adjacent its rearward edge and the opening in one is in registry with the similarly located opening in the cantilever bridging arm of the other when in properly assembled relation. Each of the openings are formed with an exterior and an interior chamfer 34 and 35 respectively with an intermediate constricted portion 36 therebetween dimensioned to be sufficiently larger than the area of the bolt member extending therethrough to enable angular movement. The outside chamfer 34 is dimensioned to receive the nut 32 or the head of the bolt 31 so as to be substantially completely concealed therein thereby to avoid interference with the positioning of the assembled device within a notch dimensioned to receive the assembled load transfer device in fitting relation and in a manner to enable free movement of the cantilever bridging arm in and out of the surrounding concrete pocket when excessive expansion of the concrete takes place.

During cure and immediately thereafter, it has been found that the concrete is incapable of development of maximum strength properties sufficient to resist being broken up in the event that substantial forces are developed. As a result, it is essential to provide means to permit relative movement between the parts of the load transfer device by an amount corresponding to the contractions which might take place during the initial stages of the setting of the concrete until such time as the concrete slab possesses sufficient strength to cause shearing of the bolt securing the parts together without deterioration. For such purpose, relative movement in amounts up to about $\frac{1}{16}$ inch is sufficient and such extended movement can be made available without interfering with the assembled relation by proper chamfer and dimension-

ing of the constricted portion as heretofore described to permit angular adjustment of the bolt during the setting process.

In use, a compression block 37 is located in the recess between the end of the cantilever arm 29 and the end of the recess in which it is received. It is preferred to locate the compression block in advance in the assembly and for this purpose, the end wall of the cantilever bridging arm is beveled inwardly from the outer edge as indicated by the numeral 38 to introduce action which cams the block inwardly against the cooperating wall of the companion part and to prevent outward displacement of the compression block 37 while in the assembled relation thereby to prevent loss or displacement. Loss of the compression block which frequently occurs when the cantilever bridging arm is formed without a bevel of the type described renders the unit inoperative because the recess would otherwise become filled with concrete and the necessary relative movement between the parts of the load transfer device would be resisted. It is preferred to make use of a compression block formed of a material similar to that of the separating strip 15 and of corresponding thickness to provide a balance between the forces existing in response to deformation of the compression block and the filler strips during expansion and contraction of the interconnected slabs of concrete.

In addition, use is made of a thin strip 39 of a compressible material, such as a pad of paper or other cellulosic sheet, dimensioned to line the area between the adjacent surfaces of the cantilever bridging arms and the recesses in which they are received to form a separator therebetween which enables relative movement between surfaces without interference because of surface roughness as occasioned in manufacture or by deterioration of the surface subsequent thereto. Without such separator, the surface roughness might otherwise freeze the parts to prevent relative movement. When used for this purpose, it is preferred to form the separating liner with a lubricant applied to the surfaces thereof or embodied therein to provide for lubricated movement in operation.

In addition to the use of the oiled pad to enhance sliding movement between the parts, the pad may be fabricated to embody a water repellent and a rust inhibitor to resist infiltration of moisture between the parts which might introduce obstructing forces and the like and which aids in the resistance to deterioration of the metal by elements existing in contact therewith particularly in this critical area wherein the forces are transmitted from one part to another while enabling relative movement.

The oiled pad is preferably dimensioned to have an edge portion 40 extending perpendicularly into the space between the lower edge of the cantilever bridging arm and the recess in which it is received to take up the space between such surfaces and to force metal to metal contact between the upper edge of the cantilever bridging arm and the body portion to the extent that little, if any, clearance is present which might require being taken up before load transmission can take place. As a result, load transmission will occur practically instantaneously, yet it is preferred that the insert be formed of a compressible material sufficient to permit a hinged action in response to warping of the parts without interfering with the operation thereof and further to minimize the tendency for corrosive freezing which might otherwise prevent relative movement between the parts.

An important feature of this invention resides in the means embodied in a device of the type described for effecting more desirable alignment of the elements with the filler strip by way of longitudinal alignment of the load transfer elements with the interconnected slabs of concrete and the development of a larger and greater bearing between the load transfer device and filler for 75

maintaining a more desirable perpendicular relationship between the device and the filler strip.

Another feature resulting from the response which will hereinafter be described resides in the more effective bearing relationship between the concrete and the elements of the load transfer device at a point where vertical loads develop the greatest stress in the concrete thereby to improve the function of the load transfer device in the use for which it is intended.

For this purpose, the body portion of each of the malleable steel castings is formed with lugs 42 and 43 extending horizontally outwardly from the side walls at the upper and lower forward edge portions of the body portion with the front faces of the lugs formed flat and substantially perpendicular to the length of the body portion and a cantilever arm extending forwardly thereof for proper alignment of the elements upon engagement with the filler strip therebetween. The remainder of the lugs 42 and 43 may be formed to various contours but it is preferred to taper the lugs rearwardly in the body portion in the form of an angular member. The upper and lower surfaces extending outwardly into the concrete, when in use, are preferably formed flat to function as shelves which add to the anchorage of the load transfer device in the concrete and are located at a point for more effective acceptance of vertical loads in the concrete where such vertical load causes the greatest stress.

Further improvement in the operational characteristics of a load transfer device embodying features of this invention results in part from the construction wherein the load carrying lug or cantilever arm is contained firmly within the recess of the companion part which is enclosed on three sides. This enclosure serves a number of important purposes. For example, it encloses the working parts of the unit to provide an improved unitary action and the side enclosures back up the paper pad in a way to offer an improved bearing contact between the opposite side of the lug and the body portion of the member in which it is received for instant load transfer. It also serves as a means for increasing the load carrying capacity of the device after initial deformation takes place. It will be apparent that when one end of the device is loaded tending to cause a hinge action, the enclosed recess brings into action the companion lug immediately upon compression of the filler formed of the lubricated cellulosic material. In addition to enclosure of the cantilever bridging member on three sides, the bridging member is also enclosed on its inner surface in a manner to provide efficient location and protection of the arm against unexpected obstructions and elements with which it might otherwise come in contact.

It will be apparent from the foregoing description that I have provided a number of improvements in load transfer devices of the type heretofore employed each of which separately and in combination improves the efficiency and the operation of the device and the assembly and utilization thereof for the purpose for which it was intended. Means enabling preassembly of the device into its relation for mounting enables the manufacture and assembly of the load transfer elements at a central location where economies may be practiced in the methods, equipment and processes for manufacture and wherein less inventory will be required thereby to enable greater efficiency in manufacture and use.

It will be understood that changes may be made in the details of construction, arrangement and operation of the device without departing from the spirit of the invention, especially as defined in the following claims.

I claim:

1. A load transfer device for use in combination with adjacent concrete slabs having a spaced relation therebetween, said device comprising a pair of substantially identical but complementary rigid members each having a body portion with a rectangular recess extending endwise from the inner edge thereof, a cantilever bridging arm

of rectangular section extending forwardly from the inner edge of the body portion and disengageably received in slidable bearing relation in the recess of the complementary member when in the assembled relation with slight clearance between the side edges, a tension arm extending curvilinearly rearwardly from the body portion with means therein for anchorage in the concrete, a compression block positioned in each of the recesses between the end of the bridging arm and the base of the recess, means for securing the members together in the assembled relation including a bolt member extending through registered lateral chamfered openings in said bridging arms, said chamfered openings being reduced for substantially line contact with said bolt member to permit relative rocking movement, tilting action and slight endwise movement between the body portions.

2. A load transfer device for use in combination with adjacent concrete slabs having a spaced relation therebetween, said device comprising a pair of substantially identical but complementary rigid members each having a body portion with a rectangular recess extending endwise from the inner edge thereof, a cantilever bridging arm of rectangular section extending forwardly from the inner edge of the body portion and disengageably received in slidable bearing relation in the recess of the complementary member when in the assembled relation with slight clearance between the side edges, a tension arm extending curvilinearly rearwardly from the body portion with means therein for anchorage in the concrete, a compression block positioned in each of the recesses between the end of the bridging arm and the base of the recess, and means for securing the members together in the assembled relation including a bolt member extending through registered lateral chamfered openings in said bridging arms, said chamfered openings being reduced for substantially line contact with said bolt member to permit relative rocking movement, tilting action and slight endwise movement between the body portions.

3. A load transfer device for use in combination with adjacent concrete slabs having a spaced relation therebetween, said device comprising a pair of substantially identical but complementary rigid members each having a body portion with a rectangular recess extending endwise from the inner edge thereof, a cantilever bridging arm of rectangular section extending forwardly from the inner edge of the body portion and disengageably received in slidable bearing relation in the recess of the complementary member when in the assembled relation with slight clear-

ance between the side edges, a tension arm extending curvilinearly rearwardly from the body portion with means therein for anchorage in the concrete, a compression block positioned in each of the recesses between the end of the bridging arm and the base of the recess, means for securing the members together in the assembled relation including a bolt member extending through registered lateral chamfered openings in said bridging arms, said chamfered openings being reduced for substantially line contact with said bolt member to permit relative rocking movement, tilting action and slight endwise movement between the body portions, and a compressible strip between the lower surface of the bridging arm and the recessed body portion to take up the clearance and to provide a bearing contact at the opposite surfaces between said members for load transfer.

4. A load transfer device for use in combination with adjacent concrete slabs having a spaced relation therebetween, said device comprising a pair of substantially identical but complementary rigid members each having a body portion with a rectangular recess extending endwise from the inner edge thereof, a cantilever bridging arm of rectangular section extending forwardly from the inner edge of the body portion and disengageably received in slidable bearing relation in the recess of the complementary member when in the assembled relation with slight clearance between the side edges, a tension arm extending curvilinearly rearwardly from the body portion with means therein for anchorage in the concrete, a compression block positioned in each of the recesses between the end of the bridging arm and the base of the recess, and means for securing the members together in the assembled relation including a bolt member extending through registered lateral chamfered openings in said bridging arms, said chamfered openings being reduced for substantially line contact with said bolt member to permit relative rocking movement, tilting action and slight endwise movement between the body portions, the cantilever bridging arm having an end which is beveled inwardly from the outer edge thereof and is in contact with the compression block to cam the block into the recess when in the assembled relation.
